UNITED STATES PATENT OFFICE

163,702

FISHHOOK DISGORGER

Charles A. Lawrence, Saugus, Mass.

Application March 27, 1951, Serial No. 14,643

Term of patent 14 years

(Cl. D31—4)

To all whom it may concern:

Be it known that I, Charles A. Lawrence, a citizen of the United States, residing at Saugus, in the county of Essex and State of Massachusetts, have invented a new, original, and ornamental Design for Fishhook Disgorgers, of which the following is a specification, reference being had to the accompanying drawing, forming a part thereof.

Fig. 1 is a top plan view of a fishhook disgorger, showing my new design.

Fig. 2 is a side elevational view.

Fig. 3 is an end elevational view.

I claim:

The ornamental design for a fishhook disgorger, as shown.

CHARLES A. LAWRENCE.
